[57] CLAIM

I claim the ornamental design for part of a chandelier, as
shown and described.

DESCRIPTION

FIG. 1 is a perspective view of a part of chandelier showing
my new design, the remainder of the chandelier being shown
in broken lines;

FIG. 2 is a side elevational view of the chandelier part, the
opposite side being identical;

FIG. 3 is a front elevational view of the chandelier part;

FIG. 4 is a rear elevational view of the chandelier part;

FIG. 5 is a top plan view of the chandelier part; and,

FIG. 6 is a bottom plan view of the chandelier part.

The broken lines shown are for illustrative purposes only
and form no part of the claimed design.
